GRINDING MACHINE

Stephen E. Woodbury, Beverly, Mass., assignor to
Reid Brothers Company, Inc., Beverly, Mass., a
corporation of Massachusetts

Application April 13, 1943, Serial No. 482,838

9 Claims. (Cl. 51—231)

This invention relates to a grinding machine and more particularly to an electrical control mechanism for an automatic surface grinding machine.

The invention has for an object to provide a machine tool such as a grinding machine, and particularly an automatic surface grinding machine with a novel and improved electrical control mechanism for controlling the operation of the machine and which is particularly useful in an automatic surface grinding machine to enable the latter to be operated in a safe, efficient and superior manner.

With this general object in view and such others as may hereinafter appear, the invention consists in the machine tool, and particularly the surface grinding machine, and in the various structures, arrangements and combinations of parts hereinafter described and particularly defined in the claims at the end of this specification.

In the drawings illustrating the preferred embodiment of the invention, Fig. 1 is a front elevation, partly in cross-section of a sufficient portion of a surface grinding machine embodying the present electrical control mechanism to enable the invention to be understood; Fig. 2 is a wiring diagram illustrating the present control mechanism as embodied in a grinding machine, to be hereinafter more fully described; Fig. 3 is a detail view of a solenoid operated brake embodied in the present grinding machine, and Fig. 4 is a modified form of braking mechanism to be referred to.

In general, a surface grinding machine embodying the invention is provided with a longitudinal work supporting table for holding and moving the parts to be machined with cross feed mechanism for progressively moving the work supporting table in a transverse direction relative to the grinding wheel. Provision is made for operating the reciprocable work supporting table through connections from a reversible motor arranged to be controlled by the movement of the table.

In the operation of the surface grinder the table is limited in its movement in either direction by the engagement of operating dogs, carried by the table, with a reversing switch designed to effect reversal of direction of the operating motor. In the event that a dog should fail to engage such reversing switch, as might occur if a dog became loosened or was improperly adjusted, the table would be free to move in its prevailing direction of movement to a po-

sition such as to overbalance the table on its support, causing damage to the table or the machine and possibly to the operator. Accordingly, one feature of the present invention contemplates the provision of a safety or limiting switch designed to be engaged to open the electrical circuit to the driving motor when the table approaches a dangerous position. In the preferred embodiment of the invention, a spring-pressed, normally closed contact member is employed in the safety switch, so that upon engagement thereof by limiting stops on the table, the power is immediately cut off not only from the table motor but also from the grinding wheel motor.

In the operation of a surface grinding machine, a possibility exists that the momentum of the table might be sufficient at times to carry the table limiting stops beyond the safety switch whereupon the spring operated contact member would immediately reestablish the circuit and permit continuance of the table movement. In order to overcome this defect the safety switch is preferably placed in the circuit in series with the solenoid of the primary magnetic switch, as will be hereinafter more fully described, whereby opening of the circuit at the safety switch will effect opening of the primary magnetic switch, so that the safety switch will not be effective to reestablish the connection to the driving motor in the event that the table overrides the safety switch, as above described, or overbalances so as to lift the limiting stops out of engagement with the safety switch.

Another feature of the present invention relates to the provision of a solenoid operated brake in the control circuit for braking the table driving motor so as to bring the latter to rest promptly upon interruption of the circuit and thus prevent the table from coasting to a dangerous position. As above described, under normal operating conditions, the table is limited in its movement in either direction by a reversing switch actuated by operating dogs carried by the table which may be adjusted to reverse the movement of the latter at predetermined limits. In practice such mechanism normally operates to reverse the table promptly at either end of its stroke. However, in prior control mechanisms in the event that the power to the table driving motor was cut off at an intermediate point in the stroke such as by turning the "on-off" switch to "off" or by pressing the stop button, the table was free to continue in motion until stopped by incidental friction. In accordance with the present invention, the solenoid of the solenoid operated brake

is preferably arranged in parallel with the primary magnetic switch solenoid so that upon pressing the stop button, the table will be brought to rest immediately at any desired position within the limits of its normal stroke. Furthermore, in the event that the table should be inadvertently moved beyond its normal limits, as above described, to cut off the power at the safety switch, the brake would likewise be applied to prevent the table from coasting to a dangerous position.

Referring now to the drawings, the present invention is preferably illustrated as embodied in a grinding machine indicated generally at 10 which is provided with a grinding wheel 12 and a longitudinally reciprocable work supporting table 14. The work supporting table is mounted to slide longitudinally upon ways 16 provided in a cross slide 20 which, in turn, is adapted to be moved transversely in ways 22, 24 formed in the top of a casing 26 mounted upon the base 28 of the machine. The grinding wheel 12 is mounted upon a spindle 13 and is driven by a spindle motor 15 as diagrammatically shown in Fig. 2.

In the illustrated surface grinding machine, the work supporting table is arranged to be reciprocated through connections including a driving sprocket gear 30 and a sprocket chain 32, 34 which extends around the lower part of the sprocket gear 30 and over idler sprockets 36, 38 respectively and connected to lugs 40, 42 depending from the opposite ends of the table.

Provision is made for driving and reversing the rotation of the sprocket gear 30 to cause the chain 32, 34 to alternately effect reciprocation of the table 14 through connections from a reversing motor 50. The gear 30 is mounted upon and arranged to rotate with a driving shaft 52 which is provided with a gear 58 fast thereon arranged to mesh with a pinion 60 comprising part of a clutch member (not shown) adapted to be operatively connected to a shaft 67. The shaft 67 is provided with a worm wheel 74 fast thereon arranged to cooperate with a worm 76 secured to the reversing motor shaft 78.

Provision is made for controlling the reversible motor 50 to effect a change in direction thereof through connections from the reciprocable work table 14. As herein shown a reversing switch 150 mounted in the cross slide 20 is arranged to be operated by dogs 152, 154 adjustably supported upon and movable with the table 14. The reversing switch comprises a slidably mounted stud 156 arranged to be reciprocated by a pivotally mounted arm 158 which is received in a slot in the stud 156. An operating arm 160, fast on the pivot shaft 162 is provided with pins 164, 166, arranged to be engaged by the dogs 152, 154 respectively at the end of the predetermined longitudinal movement of the table. The switch stud 156 is provided with contacts 168, 170 and in operation, when a dog engages the switch 150, it operates to first open the prevailing circuit to the motor 50 and then close a second circuit to operate the motor in the reverse direction. A handle 161 is also provided on the operating arm 160 to permit the switch to be manually operated when desired.

As illustrated in Figs. 1 and 2, a safety switch 172 is located beneath the table 14 substantially centrally in the machine. It is operative to open the entire circuit in the event the dogs 152, 154 are removed or become loosened. The safety switch is arranged to be operated by cam pieces

174, 176 supported on the underside of the table 14 either of which is arranged to engage and depress the switch member 172 to open the circuit at contacts 178 in the event that the table should override or inadvertently fail to engage the reversing switch 150.

Referring now particularly to Fig. 2, the illustrated controlling apparatus comprises a primary circuit including connections to the grinding head or spindle motor 15, and the reversing motor 50. Stop and start switches 182, 184 are arranged to open and close a relay circuit to the solenoid 185 of a primary magnetic switch 186-187-188 which closes the circuits to the grinding head motor and to the reversing motor at contacts 188 and 189. The reversing switch indicated at 150 operates to alternately open one circuit and close another to the solenoids 190, 192 for alternately opening and closing the circuits to the reversing motor 50 at contacts 194, 195, 196 and 197 whereby the direction of rotation is reversed.

From the description thus far it will be observed that under normal operating conditions, when the "on-off" switch 198 is moved to its "on" position and the start button 182 is pressed the solenoid 185 of the primary magnetic switch 186-187-188 is energized to close the circuits to the spindle motor 15 and the table motor 50, and that the direction of rotation of the motor 50 will be reversed to reciprocate the table 14 each time the latter reaches its limit of movement in either direction as determined by the adjustment of the reversing dogs 152, 154. In the event that the reversing dogs become loosened or are improperly adjusted, or, upon failure of the reversing switch 150, the table will continue to be driven in the prevailing direction until either of the limiting stops 174, 176 engages the spring-pressed safety switch 172. As herein shown, the safety switch contacts 178 are preferably arranged in series with the primary magnetic switch solenoid 185. With this construction, when the circuit is interrupted at the safety switch contacts 178, the primary magnetic switch solenoid will be deenergized to open the circuits to the spindle motor 15 and the table motor, and, such circuits cannot be reestablished until two conditions are satisfied. First, the table must be manually moved back to within its normal range of movement to reset the safety switch contacts and second, the start button must be pressed. In this manner, the possibility of re-establishing the circuit through the safety switch contacts alone is eliminated, since, in the event the momentum of the table should carry the limiting stops beyond the safety switch, or, in the event the table should be overbalanced and lift up so as to permit the safety switch contacts to again be connected, it would still be necessary to press the start button before the circuits to the motors would again be reestablished. In any event, positive driving of the table beyond the limit defined by the safety switch is entirely terminated.

The solenoid brake, as shown in Figs. 1 and 3, and indicated generally at 200 comprises a shoe type spring set brake which is maintained in its inoperative or off position when the current is on and which is released to apply the brake when the current is cut off. As herein shown, the motor shaft 78 may be provided with a relatively small pulley 202 and the braking unit may be supported on a shelf 204 adjacent the motor. In operation, when the solenoid 206 is energized, the

brake shoes 208 are held away from the pulley to permit normal operation of the machine. However, when the circuit is interrupted as above described, the solenoid 206 is deenergized thus releasing the spring 210 to permit the brake shoes 208 to be applied to the wheel 202. As diagrammatically illustrated in Fig. 2, the brake solenoid 206 is arranged in parallel with the primary switch solenoid 185 so that upon interruption of the circuit at either the "on-off" switch 198, the stop button 184 or the safety switch 172 the brake solenoid will be deenergized to bring the table to rest promptly.

Referring now to Figs. 1 and 4, a modified form of braking mechanism, indicated generally at 80, comprises an electrically operated brake or friction shoe 82 adapted to frictionally engage the underside of the work table 14 when the current is cut off, and which is electromagnetically maintained in its inoperative position when the current is on. As herein shown, the modified braking unit includes a solenoid 84 arranged to hold the brake shoe 82 down away from the underside of the table 14 against the resistance of a pair of coil springs 86. In the circuit shown in Fig. 2, the solenoid 84, see Fig. 4, may replace the solenoid 206 shown in Fig. 2, so that in operation, when the solenoid 84 is energized, the friction shoe 82 is held away from the reciprocable table 14 to permit normal operation of the machine. However, when the circuit is interrupted, as above described, the solenoid 84 is deenergized thus releasing the springs 86 to apply the brake.

From the above description it will be seen that the present invention enables the machine to be controlled in a simple and efficient manner to provide a maximum of safety for the operator and a minimum of liability of damage to the machine.

Although the present control mechanism is preferably illustrated herein as embodied in a surface grinding machine, it will be understood that the invention may be used with advantage in other forms of machine tools wherein movement of certain parts are desired to be limited in their extent of movement so as to maintain the machine in a safe operating condition.

While the preferred embodiment of the invention has been herein illustrated and described, it will be understood that the invention may be embodied in other forms within the scope of the following claims.

Having thus described the invention, what is claimed is:

1. In a grinding machine, in combination, a reciprocable work supporting table, driving mechanism for reciprocating said table including a reversing motor, a primary electrical circuit for said motor including a solenoid operated primary switch, a stopping and starting switch for controlling the action of said primary switch, a reversing switch for effecting reversal of the motor, means carried by the table for operating said reversing switch when the table is moved into a predetermined position in either direction, and a safety switch arranged to be engaged by the table to open the circuit to the primary switch and thus stop the motor in the event that the table should inadvertently override said predetermined position, said safety switch being arranged in series with said primary switch solenoid whereby to interrupt the motor circuit and prevent reestablishment thereof until the table is moved back to within its normal range of movement and the starting switch is operated.

2. In a grinding machine, in combination, a reciprocable work supporting table, driving mechanism for reciprocating said table including a reversing motor, a primary electrical circuit for said motor including a solenoid operated primary switch, a stopping and starting switch for controlling the action of said primary switch, a reversing switch for effecting reversal of the motor, means carried by the table for operating said reversing switch when the table is moved into a predetermined position in either direction, and a safety switch arranged to be engaged by the table to open the primary switch and thus stop the motor in the event that the table should inadvertently override said predetermined position.

3. In a grinding machine, in combination, a reciprocable work supporting table, driving mechanism for reciprocating said table including a reversing motor, a primary electrical circuit for said motor including a primary magnetic switch, a stopping and starting switch controlling the action of said primary switch, a reversing switch for effecting reversal of the motor, a limiting dog carried at each end of said table for operating said reversing switch when the table is moved into a predetermined position in either direction, and a spring-pressed safety switch arranged to be engaged by the table to open the primary switch and thus stop the motor in the event that the table should inadvertently override said predetermined position, said safety switch being arranged in series with the solenoid of said primary magnetic switch whereby to prevent reestablishment of said motor circuit until the table is moved back to within its normal range of movement and the starting switch is also operated.

4. In a grinding machine, in combination, a reciprocable work supporting table, driving mechanism for reciprocating said table including a reversing motor and a motor shaft, an electrical circuit for said motor including a solenoid operated primary switch, a stopping and starting switch for controlling said primary switch, a reversing switch for effecting reversal of the motor, means carried by the table for operating said reversing switch when the table is moved into a predetermined position in either direction, and a single centrally located safety switch arranged to be engaged by the table to open the primary switch and thus stop the motor in the event that the table should inadvertently override either of said predetermined positions, said safety switch being arranged in series with said primary switch solenoid whereby to prevent reestablishment of said motor circuit until the table is moved back to within its normal range of movement and the starting means is operated, a spring-actuated brake associated with said motor shaft, and a solenoid connected in parallel with the primary switch solenoid arranged to release said brake to bring said motor to an abrupt stop when said stopping means or said safety switch is operated to interrupt the current to said primary switch.

5. The combination with a machine tool provided with a movable member arranged to normally travel within predetermined limits, of driving mechanism for said movable member including a motor, a primary circuit for said motor including a solenoid operated primary switch, and a safety switch connected in series with said primary switch solenoid and arranged to be engaged by said movable member to open said primary switch and thus stop the motor in the event that

said movable member inadvertently overrides its normal predetermined limits.

6. The combination with a machine tool provided with a movable member arranged to travel within predetermined limits, of driving mechanism for said movable member including a motor and a motor shaft, a circuit for said motor including a solenoid operated primary switch, and a safety switch connected in series with said primary switch solenoid and arranged to be engaged by said movable member to open said primary switch and thus stop the motor in the event that said movable member inadvertently overrides its normal predetermined limits, a spring-operated brake associated with said motor shaft, and a solenoid connected in parallel with said primary switch solenoid arranged to release said brake to bring said motor to an abrupt stop when said primary switch is opened.

7. In a grinding machine, in combination, a reciprocable work supporting table, driving mechanism for reciprocating said table including a reversing motor, an electrical circuit for said motor including a solenoid operated primary switch, a reversing switch for effecting reversal of the motor, means carried by the table for operating said reversing switch when the table is moved into a predetermined position in either direction, and a solenoid operated brake connected in parallel

with the primary switch solenoid arranged to engage said table and bring it to an abrupt stop when said primary switch is opened.

8. In a grinding machine, in combination, a reciprocating work table, a reversible motor for driving the table, a grinding head having an individual motor, a primary circuit for operating both motors including an electro-magnetic switch, means operated by the table at each end of its normal travel, for reversing the table motor, and a single safety switch operated by the table in reaching a position beyond its normal path of travel in either direction for opening said electro-magnetic switch and stopping both the said motors.

9. In a grinding machine, in combination, a reciprocating table, a reversible motor therefor, a motor circuit including primary and reversing switches, dogs carried by the table for operating the reversing switch at each end of the normal travel of the table, a single safety switch located substantially centrally beneath the path of the table for controlling said primary switch, and separate means carried by the table for tripping the safety switch and operating when the table moves in either direction beyond its normal path of travel.

STEPHEN E. WOODBURY.
